UNITED STATES PATENT OFFICE.

Z. COLEMAN ROBBINS, OF WASHINGTON, DISTRICT OF COLUMBIA, ASSIGNOR TO A. MARTIN.

MILL FOR COMPRESSING AND GRINDING GRAPES AND OTHER SMALL FRUITS.

Specification of Letters Patent No. 13,448, dated August 14, 1855.

To all whom it may concern:

Be it known that I, Z. COLEMAN ROBBINS, of the city of Washington, in the District of Columbia, assignor to Anson Martin, of 5 Norwich, in the State of Connecticut, have invented a new and improved machine for grinding grapes and other small fruit by the same operation that enables a large portion of the juice to be pressed therefrom 10 without breaking the seeds; and I do hereby declare that the following is a full and exact description thereof, reference being had to the accompanying drawings, making a part of this specification, Figure 1, being a top 15 view; Fig. 2, a side elevation; Fig. 3, a vertical section in the line $x-x$ of Fig. 1; Fig. 4, a vertical section in the line $y-y$ of Fig. 1, and Fig. 5 a sectional view of a portion of the machine detached.

20 Similar letters indicate like parts in all the figures.

The frame of my improved grape grinder, may be constructed in any well known manner.

25 A, B, are the grinding cylinders, the peripheries of which are generally corrugated. The journals of the shafts e, f , of the grinding cylinders, are received into journal boxes which are secured to the portions s, s , 30 of the frame. The boxes of the shaft e , are permanently secured in their positions, and the boxes q, q , of the shaft f , are arranged in such a manner that they can be moved by means of the set screws p, p , 35 and be secured by means of the set screws t, t , which arrangement, enables the grinding cylinders to be placed at any desired distance from each other.

The grinding cylinders A, B, are connected to each other by means of the cog wheel c , on the shaft e , and the pinion d , on the shaft f , whose teeth work into each other, which arrangement, causes the cylinder B, to revolve at a considerably higher speed 45 than the cylinder A. The ends of the grinding cylinders A, B, are closely embraced between the sides m, m , of the grape box. The ends n, n , of the said grape box, are secured to its sides in oblique positions, with 50 their inner ends nearly in contact with the peripheries of the grinding cylinders. A reciprocating compressor i , works in grooves in the sides m, m , of the grape box, which rise vertically from the space between the 55 grinding cylinders. The said compressor i , is connected to the outside metallic plates

h, h , by means of the screw v, v , which pass through slots in the sides m, m , of the grape box. A reciprocating motion is imparted to the compressor i , in the following manner, viz: An upward movement is imparted to said compressor by means of the springs j, j , which rest on offsets u, u , on the outer sides of the grape box, and whose upper ends bear against arms at the upper ends of 60 the plates h, h , as shown in Figs. 2 and 4, and a downward movement is imparted to the said compressor, by means of the cam wheels g, g , on the shaft e , whose projections, as they are rotated, strike against 65 arms at the lower extremities of the said 70 plates h, h .

Motion may be imparted to the grinding cylinders and to the compressor i , by means of a crank on the shaft e , or by any other 75 manner. The compressor i , may either work in grooves in the sides of the grape box, or it may work on any suitable ways secured to the said sides of the box.

The grapes, (or other fruits,) to be acted 80 upon, are placed within the box m, m, n, n , and when motion is imparted to the grinding cylinders, and the compressor i , the action of the said cylinders is to carry the grapes inward, and the action of the compressor is to force the grape down between 85 said cylinders. The rapid movement of the periphery of the cylinder B, acting against the slower moving periphery of the cylinder A, tears the skins and pulps of the grapes 90 to pieces, as they pass between said cylinders; and in their disintegrated state the grapes fall into the trough k , in the proper condition to be acted upon by the press. The combination of the compressor with 95 the grinding cylinders, in my grape grinding machine, greatly adds to its performance, and enables a larger proportion of juice to be forced out of the fruit during the grinding process than would otherwise 100 be the case.

In adjusting the relative positions of the grinding cylinders and the compressor, they must not be allowed to come into sufficiently close contact with each other to break the 105 seeds of the fruits, which they are made to operate upon.

I am aware that a reciprocating knocker or compressor has been employed within the hopper of fruit grinding machines in combination with a concave and a grinding cylinder; also that two cylindrical rollers have 110

been employed in combination with a feeding roller within the fruit hopper. I disclaim both of these arrangements, also these devices separately considered. But

5 What I do claim as my invention and desire to secure by Letters Patent, is—
The combination and joint action of the

compressor *i*, and the cylinders A, and B, for compressing and grinding purposes, substantially as herein set forth.

Z. COLEMAN ROBBINS.
